UNITED STATES PATENT OFFICE.

CLAUDE SINTZ, OF DETROIT, MICHIGAN.

GOVERNOR FOR EXPLOSIVE-ENGINES.

1,117,608.

Specification of Letters Patent. Patented Nov. 17, 1914.

Application filed November 1, 1913. Serial No. 798,618.

To all whom it may concern:

Be it known that I, CLAUDE SINTZ, a citizen of the United States of America, residing at Detroit, in the county of Wayne and State of Michigan, have invented certain new and useful Improvements in Governors for Explosion-Engines, of which the following is a specification, reference being had therein to the accompanying drawings.

10 My invention relates to governors for explosion engines and has among the objects thereof to provide a simple and efficient construction for adjusting the governor valve, and to provide a device in which the proper 15 seating of the valve will at all times be insured.

Other objects of the invention will more fully, hereinafter appear.

The invention resides in the peculiar construction, arrangement and combination of parts as hereinafter set forth and as particularly pointed out in the claims.

In the drawings,—Figure 1 is a sectional side elevation of the device embodying the 25 invention; Fig. 2 is a section on the line $x-x$ of Fig. 1.

A designates a casing forming a portion of the induction conduit leading to the engine, B the inlet therefor, and C the outlet. 30 D is the valve seat composed of a cylindrical member e tending transversely of the casing A and having the opposite ends thereof seated in bearings E F in the casing. This valve seat is provided with a plurality 35 of slots H in the upper side thereof, and with corresponding slots I in the lower side, providing a plurality of spaced segmental portions I. The valve J is arranged in the cylindrical member D for longitudinal sliding movement, and is composed of a member 40 having a plurality of spaced circular sections K corresponding in number to the slots H and each of a width slightly greater than these slots. When the valve is open the 45 parts are as shown in Fig. 1, but when the valve is adjusted longitudinally the slots H will be more or less restricted, or completely closed, according to the adjustment of the valve—as will be readily understood.

50 The shifting of the valve is controlled by a centrifugal governor composed of arms L

M arranged at substantially diametrically opposite points upon a sleeve N.

O are springs connecting the weighted ends P and tending to hold the weighted ends at 55 their inward position of adjustment, in the usual manner. The sleeve N is journaled upon an extension Q of the casing A and is provided with a sprocket R which is driven in any suitable manner from the crank shaft. 60

S is a longitudinally shiftable shaft slidably arranged within a bore T in the extension Q and carrying at its outer end a thrust bearing U engaged by the ends V of the centrifugal arms. The inner end W of the 65 shaft S abuts against the inner end of the valve J.

The opposite end of the casing from the centrifugal governor is provided with a head A' which closes the outer end B' of the 70 valve D. This head is provided with a bearing C' within which is arranged for longitudinal sliding movement a shaft D', the inner end of which abuts against the outer end of the valve J.

75 E' is a lever pivoted at F' to an arm G' suitably mounted upon the casing A, and this lever has the end F'' thereof engaging the outer headed end of G' of the shaft D'. Connected to the opposite end H' of the 80 lever E' is a spring I' that tends to move the lower end F'' of the lever E' inwardly and thereby exerts a yielding pressure upon the shaft D', tending to move the latter in a direction to maintain the valve open. 85

With the construction so far described, when the speed of the engine becomes too great, the governor arms P will be thrown outward by centrifugal action, since as before stated, the sleeve N is driven from the 90 crank shaft. The outward movement of the governor arms will move the shaft S longitudinally inward, which will shift the valve to variably restrict the ports H, thereby restricting the flow of gases through the casing A. When the speed of the engine decreases so that the spring O of the governor arms moves the latter inward, the spring I' will act upon the shaft D' through the medium of the lever E' to move the 95 valve in the opposite direction. The speed at which the governor arms are thrown out 100

ward to shift the valve is regulated by means of an adjusting bolt J' which has a threaded engagement with a fixed bearing K' and has one end connected to the spring I' . Thus by adjusting the bolt J' the tension of the spring I' may be varied, and since the centrifugal arms must move the valve against the tension of the spring I' , this will increase the force required to move the governor arms outwardly. By this manner of adjustment the governor may be very accurately regulated.

In order to reduce the wear between the valve and its seat to a minimum and also in order to insure that the valve will be properly seated, the ends of the shafts S and D' are not connected to the valve but merely abut against the opposite ends thereof, and the valve is arranged within this seat so as to be free to float therein. The suction created in the casing A during the working of the engine will draw the valve upwardly against the segments G in the upper portion of the valve seat, and therefore, will insure a proper seating of the valve and will also reduce the wear between the valve and its seat to a minimum.

By having the yielding means which opposes the action of the governor arranged at the opposite end of the valve from the centrifugal governor mechanism, this yielding means will automatically take up any wear in the governor parts and thereby insure greater accuracy in the operation of the valve and avoiding what is generally known as back lashing of the parts.

What I claim as my invention is:—

1. A governor for explosion engines, comprising a casing provided with a valve seat, a longitudinally shiftable valve therein, centrifugal means, a member movable longitudinally by said centrifugal means, and a connection between said member and the valve at one end of the latter permitting a lateral movement of the valve relative to said member.

2. A governor for explosion engines, comprising a casing provided with a valve seat, a longitudinally shiftable valve therein, centrifugal means, a member movable longitudinally by said centrifugal means, a connection between said member and the valve at one end of the latter permitting a lateral movement of the valve relative to said member, a second longitudinal movable member, a connection between said second member and the valve at the opposite end of the latter permitting a lateral movement of the valve relative to said second member, and yieldable means acting upon the second member and opposing the centrifugal means.

3. A governor for explosion engines, comprising a casing provided with a valve seat, a longitudinally shiftable valve therein, cen-

trifugal means, and a member movable longitudinally by said centrifugal means and abutting against one end of the valve but unattached thereto, whereby lateral movement between said member and the valve is permitted.

4. A governor for explosion engines, comprising a casing provided with a valve seat, a longitudinally shiftable valve therein, centrifugal means, a member movable longitudinally by said centrifugal means, said member and said valve having abutting but unconnected faces, whereby lateral movement between said member and the valve is permitted, and means for yieldingly holding said faces in engagement.

5. A governor for explosion engines, comprising a casing provided with a valve seat, a longitudinally shiftable valve therein, a longitudinally shiftable shaft having one end abutting against one end of the valve but unattached thereto, centrifugal means engaging the opposite end of said shaft, a second shaft abutting against the opposite end of the valve but unattached thereto, whereby lateral movement between said valve and the second shaft is permitted, and yielding means engaging the last-mentioned shaft and opposing the centrifugal means.

6. A governor for explosion engines, comprising a casing provided with a valve seat, a longitudinally shiftable valve therein, a longitudinally shiftable shaft having one end abutting against one end of the valve but unattached thereto, centrifugal means engaging the opposite end of said shaft, a second shaft abutting against the opposite end of the valve but unattached thereto, yielding means engaging the last-mentioned shaft and opposing the centrifugal means, and means for regulating said yielding means.

7. The combination with a casing provided with a valve seat, a longitudinally shiftable valve therein, said casing having an extension in alignment with the valve seat, a sleeve rotatively journaled upon said extension, centrifugal arms carried by said sleeve, a shaft longitudinally shiftable mounted in said extension, one end of said shaft abutting against but unconnected to one end of the valve, the opposite end of said shaft being adapted to be engaged by the centrifugal arms, a bearing positioned upon the casing on the side thereof opposite from said extension, a second shaft slidably mounted in said bearing and having one end thereof abutting against the other end of the valve but unconnected thereto, and yielding means acting upon the second shaft to oppose the action of the governor arms.

8. A governor for explosion engines, comprising a casing provided with a valve seat, a longitudinally shiftable floating valve e'

gaging said seat, centrifugal means, and a connection between said centrifugal means and said valve for shifting the latter by the centrifugal means, said connection permitting a relative lateral movement between said valve and said connection.

In testimony whereof I affix my signature in presence of two witnesses.

CLAUDE SINTZ.
